UNITED STATES PATENT OFFICE.

FREDERICK JACKSON, OF KARNS CITY, PENNSYLVANIA.

SAND PUMP AND BAILER.

SPECIFICATION forming part of Letters Patent No. 595,306, dated December 14, 1897.

Application filed August 28, 1897. Serial No. 649,883. (No model.)

To all whom it may concern:

Be it known that I, FREDERICK JACKSON, a citizen of the United States, residing at Karns City, in the county of Butler and State of Pennsylvania, have invented certain new and useful Improvements in Sand Pumps and Bailers; and I do hereby declare the following to be a full, clear, and exact description of the invention, such as will enable others skilled in the art to which it appertains to make and use the same.

This invention relates to improvements in sand-pumps, and is intended principally for use in oil-wells for removing the sand, mud, and the like from the same.

The invention consists of certain novel constructions, combinations, and arrangements of parts, which will be more particularly set forth and claimed.

In the accompanying drawings, forming part of this specification, Figure 1 represents a side elevation of the devices embodying my invention, the interior parts being shown in their depressed position by dotted lines. Fig. 2 represents a central vertical section through the same, the piston being in its elevated position. Fig. 3 represents a detail central vertical section through the lower portion of the pipe, showing the application of the valve-re-30 moving tool. Fig. 4 represents an enlarged detail perspective view of a modified form of said tool applied in position.

1 in the drawings represents the tube or cylinder of my improved pump, 2 the removable valve, and 3 the piston. The cylinder or pipe 1 is formed near its lower end with two apertures 4, arranged on diametrically opposite sides and adapted to receive two locking-plungers 5, mounted upon the respective lower ends of flat springs 6, which latter are secured at their upper ends to the side of the tube 1. The tension of said springs 6 normally holds the locking plungers or studs 5 in their respective recesses 4, but permits of the same being withdrawn at will to release the valve 2, as hereinafter described. The edges of said springs 6 are preferably beveled, so that a suitable unlocking-tool may be forced under the same to withdraw the studs 5 from the recesses 4. The said valve 2 comprises a hollow valve-casing 7, adapted to fit within the lower end of the tube 1 and having an annu-

lar external shoulder 8, upon which the lower end of said tube rests. The lower edge of said casing 7 is preferably scalloped, as shown at 9, to permit the ready entrance of the sand, water, and other substances into the said casing when the same is resting upon the bottom of the well. The upper portion of said casing 7 is formed upon diametrically opposite sides with apertures 10^a, into which the inner ends of the studs 5 spring, so as to hold said casing firmly in position. An inlet-aperture 11 is formed in the top of said casing and is covered by an upwardly-opening flap-valve 12, whereby the upward passage of water through said casing is permitted, but any reverse movement of the water prevented. The piston 3 is adapted to be operated in the tube 1 to draw the water, sand, and other substances into the same and then lift said tube with its load out of the well. This piston comprises a head 13, having upper and lower screw-threaded extensions 14 and 15, respectively. A packing or elastic washer 16 is mounted on said extension 15 and is adapted to be held securely in place by a screw-threaded locking-nut 17, also applied upon said extension. A vertical passage 18 is formed through the head 13 and extensions 14 and 15 and terminates at its upper end in a valve-seat 18^a, upon which rests a spherical valve 19, so as to normally close the upper end of said passage against any downward egress of water. The said valve 19 is confined in the proper position upon its valve-seat by a valve-cage 20, having a screw-threaded sleeve 21, which screws upon the upper extension 14. Said cage 20 is suitably connected to the piston rod or stem 22, which passes up through the tube 1 and is connected to the operating devices. Said valve-cage 20 is formed with a nut or washer 23, having a central stud or extension 24, upon which rests the lower end of the coiled spring 25, the latter surrounding the rod 22. The upper end of the tube 1 is closed by a socketed head 26, which latter is secured in position by suitable rivets or bolts 27.

It will be observed from the foregoing description that as the piston 3 approaches the upper end of the tube 1 the upper end of the coiled spring 25 engages the under side of the head 26, and thus prevents any further up-

ward movement of said piston independently of the tube 1. Said spring 25 thereby absorbs all shock or sudden concussion, which would be thrown ordinarily upon the devices by the 5 striking of the upper portion of the piston against the under side of the head 26. Openings 28 are formed in the tube 1, so that as said tube is lowered into the well the liquid passing into the same will not be forced up 10 through the valve 19, but will pass out of the said openings. After said tube 1 has been filled and drawn up out of the well the springs 6 are operated, as described, and the valve 2 permitted to drop from the lower end of the 15 tube, thus allowing the escape of the contents of said tube. The disengagement of said valve from the lower end of the tube is preferably accomplished by a tool such as shown in Fig. 4 and which comprises a hook portion 20 31, adapted to pass partly about said tube, and curved wedge-shaped arms 32, adapted to extend on either side of the tube and between it and said springs 6. A suitable operating-handle 33 is provided upon the devices, 25 whereby it may be operated to cause the said wedge-shaped portions 32 to pass under the springs 6 by engaging the beveled edges of the same.

It is sometimes desirable, because of the 30 character of the soil through which the well is driven, to locate the springs for operating the locking-studs upon the interior of the valve itself and have them spring out through the apertures of the valve into the apertures 35 of the tube. The operation in this application of my invention is practically the same as before, with the exception that the valve is disengaged from the tube by forcing the outer ends of the spring-pressed studs inward. This 40 is accomplished, as shown in Fig. 3, by a scissors-shaped device 34, having disengaging studs 35 mounted at its opposite ends and adapted to engage said outer ends of the studs mounted upon the springs.

45 By the employment of my invention the valve may be instantly released from the lower end of the lifting-tube without turning or

without the employment of any force other than that necessary to operate the disengaging-tool. The shock incidental to the termination of the upward movement of the piston will be absorbed because of the peculiar construction of the spring 25, which is interposed between the upper end of the piston and the under side of the head 26. 50

Having thus described my invention, what I claim as new, and desire to secure by Letters Patent, is— 55

1. In a pump, the combination with a suitable tube, of a valve removably mounted at the lower end of the same and provided with a plurality of apertures, spring-pressed studs mounted on the lower end of said tube and adapted to enter said apertures to hold the valve in position, and a piston mounted in 65 said tube, substantially as described.

2. In a pump, the combination with a suitable tube, of springs located at the lower end of said tube and carrying plungers or studs which normally project through the wall of 70 said tube, a valve comprising a hollow casing formed with a plurality of openings adapted to be engaged by said studs, and a valve proper mounted on said casing, substantially as described.

3. In a pump, the combination with a suitable tube, of springs located at the lower end of the same and provided with studs or plungers which project through the walls of said tube, a valve-casing provided with apertures 80 adapted to be engaged by said studs, a valve mounted on said casing, a piston mounted in said tube, a piston-rod connected to said piston, a head at the upper end of said tube, and a coiled spring interposed between said head 85 and said piston, substantially as described.

In testimony whereof I have signed this specification in the presence of two subscribing witnesses.

FREDERICK JACKSON.
